UNITED STATES PATENT OFFICE

JAKOB RIOTTE, OF NOWAWES, GERMANY

ELECTRICAL RESISTANCE

Application filed October 1, 1928, Serial No. 309,566, and in Germany October 7, 1927.

This invention relates to electrical resistances, and more particularly to that type of resistance which substantially comprises a column or pile of superimposed carbon discs. 5 Electrical resistances of the kind in question have the power of greatly varying their ohmic value under varying pressure. In order to obtain the greatest possible amount of play in the extent of resistance introduced by the 10 apparatus the mechanism causing the varying pressure to be applied requires on the one hand to distribute the pressure equally over the entire cross-section of the pile or column, while at the same time the same must 15 be capable of relieving the column entirely.

These requirements necessitate a position of the pressing faces of the mechanism exactly parallel to the end faces of the column, and are, particularly in the case of a large 20 cross-section of the column, only capable of being fulfilled with an exactitude of construction which is relatively expensive.

Adaptation of the one or both pressing faces to the end faces of the column or pile 25 might be effected in the known manner by furnishing the pressure members with ball joints. This, however, is associated with the disadvantage that the freely movable pressure members, in accordance with the particular arrangement, may have the tendency 30 to tilt or otherwise assume an incorrect position when no longer exerting pressure on the pile of carbon.

The subject matter of the present invention 35 is an arrangement by means of which the pressure members, on the one hand, are capable of exactly adapting themselves to the end faces of the pile, while on the other hand they nevertheless maintain the position 40 once assumed even should they move out of contact with the pile. This is accomplished by furnishing the joints of the pressure members with friction means so calculated that 45 the pressure member is capable of maintaining the position once assumed in relation to the organ to which the same is attached, even should the carbon pile exert no further reaction on the same, while on the other hand it 50 is enabled to adapt itself to the end face of

the pile when the pressure exceeds a certain amount.

The invention will now be described more fully with reference to the accompanying drawing, in which

Figs. 1 and 2 show two possible forms of embodiment.

Referring to Fig. 1, A represents the pile or column of carbon discs, and B a lever, which is acted upon by the force C and compresses the pile A to a greater or lesser extent. D is the one pressing face which, according to the invention, is connected in movable manner to the lever B, the same in the case of the present embodiment being rotary about the ball E in the cup F. Since the member D due to its unstable position might have the tendency to tip over, and consequently, when the column or pile were wholly relieved, assume together with the column a tilted position, so that the upper end of the column would not be released, the ball E is according to the invention furnished with a friction device consisting of a sheet metal ring G and pressure screws J. 70 By means thereof the plate D is maintained in its normal relative position to the lever B, while on the other hand the friction at the ball E is nevertheless sufficiently small that adjustment is possible in relation to the face 75 of the column upon the application of reasonable pressure.

Adjustability by means of friction of the one pressing face of the mechanism is of particular importance if in place of one column 80 or pile A two or more are arranged side by side and are simultaneously acted upon by the same pressing faces D and K.

Fig. 2 shows a form of embodiment in which two columns or groups of columns A 90 are acted upon by two different, movable pressing members. In such an instance it is desirable to also connect the beam B distributing the pressure to the two columns A 95 movably with the pressure members M, the movability likewise being limited in suitable manner. This is necessary in order upon difference in weight on the two sides to prevent the unstable beam from tipping towards the one side. For this purpose the pressure 100

members M are furnished with a friction means E similar to that in the case of the first embodiment. In this manner the pressure C, on the one hand, is distributed perfectly evenly over the two columns A, while on the other hand a tipping of any of the parts, which would make complete relief of the columns impossible, is prevented.

What I claim as new and desire to secure 10 by Letters Patent is:

1. In a form of embodiment of an electrical resistance, a pile of carbon discs constituting the resistance proper, a lever for applying varying pressure to the said pile, a 15 plate resting against one end of the said pile, a ball joint between the said plate and the said lever so as to enable the said plate to adapt itself to the said pile, and a friction means provided at the said joint in order to 20 restrict the free movability of the plate.

2. In a form of embodiment of an electrical resistance, a plurality of piles of carbon discs situated side by side, means for applying varying pressure to the said piles, a beam 25 for distributing the said pressure equally over the said piles, plates resting against the ends of the said piles, connecting members between the said plates and the said beam, joints between the said plates and the 30 said connecting members, joints between the said beam and the said connecting members, and friction means at the said joints in order to restrict the free movability of the plates.

3. Apparatus according to claim 1 in 35 which said friction means are adjustable.

In testimony whereof I have affixed my signature.

JAKOB RIOTTE.
